COMPRESSED AIR INTENSIFIER

George Norman Cadbury, West Bromwich, England, assignor to E. M. B. Company Limited, West Bromwich, England

Application June 23, 1941, Serial No. 399,375
In Great Britain August 21, 1940

1 Claim. (CL 230—52)

In the specification of my patent application No. 347,323 I have described an invention relating to compressed air intensifiers for use more particularly with die casting machines. The present specification is concerned with a modification of the said invention whereby the apparatus supplied by the intensifier can readily be enabled to meet a wide range of different working conditions.

The present invention comprises in combination an intensifier as claimed in my earlier specification above mentioned, operating valves associated with the low pressure part of the intensifier, other operating valves associated with the high pressure part of the intensifier and interconnected with the first mentioned valves, a by-pass situated between the first mentioned valves and the delivery side of the second mentioned valves, a non-return valve in the by-pass, and also a regulating valve or valves in the by-pass.

The accompanying drawing is a diagrammatic sectional elevation of apparatus constructed in accordance with the invention for supplying compressed air to a die casting machine or other apparatus.

In carrying the invention into effect as shown, I employ an intensifier comprising a slideable ram having a pair of coaxial parts *a*, *b* of different diameters and mounted in a cylinder having parts *c*, *d* of corresponding different diameters as described in my specification above mentioned. Movement of the ram *a*, *b* in one direction is effected by compressed air acting on the outer end of the larger part *a* of the ram, and the return is effected by gravity, compressed air or a spring. Air is admitted to and exhausted from the larger or low-pressure part *c* of the cylinder under the control of a pair of spring-loaded poppet type valves *e*, *f* arranged in a chest *g*, these valves being operable by a common lever *h*. The valve *e* controls communication between a compressed air supply pipe *i* and another pipe *j* leading to the low-pressure part *c* of the cylinder, whilst the valve *f* controls communication between the pipe leading to the low-pressure part *c* of the cylinder and an outlet pipe *k* leading to atmosphere through a hollow extension *c*¹ of the cylinder. Movement of the lever *h* in one direction opens the valve *e* and allows the valve *f* to close, and opposite movement of the lever is accompanied by the reverse effect.

The smaller or high-pressure part *d* of the cylinder is provided with a non-return valve *m* past which compressed air from a branch pipe *n* communicating with the supply pipe *i* can flow 55

into that part of the cylinder. Also the high-pressure part *d* is provided at its outer end with a delivery pipe *o* having associated with it a pair of spring-loaded poppet valves *p*, *q* similar to those above described. The valves *p*, *q* are arranged in a chest *r* and are operable by a common lever *s*. The valve *p* controls communication between the delivery pipe *o* and another pipe *t* leading to the die casting ma-

chine *v* or other apparatus to be supplied with compressed air, whilst the valve *q* controls communication between the latter pipe and an outlet *u* to atmosphere in the chest *r*. Movement of the lever *s* in one direction opens the valve *p* and allows the valve *q* to close, and opposite movement of the lever has the reverse effect.

The two valve-operating levers *h*, *s* are interconnected by, for example, a link *w*, so that the valve *e* for admitting compressed air to the low-pressure part *c* of the cylinder is opened and closed concurrently with the valve *p* for admitting compressed air from the high-pressure part *d* of the cylinder to the casting machine *v* or other apparatus, and so that the valve *f* for exhausting air from the low-pressure cylinder part is opened and closed concurrently with the valve *q* for releasing air from the casting machine or other apparatus. By interconnecting the operating levers of the two pairs of valves I obviate any risk of accidental escape from the intensifier, while the latter is not in action, of air admitted to the high-pressure part of the cylinder.

For some purposes it is desirable to set a lower limit to the pressure at which air is discharged from the high-pressure part *d* of the cylinder. In other words, it is desirable to ensure that the pressure shall reach a predetermined value before discharge commences after the intensifier has been set in motion. To meet this requirement, I secure or form on the outer end of the high-pressure cylinder part *d* a hollow cylindrical extension *d*¹ in which is slidably mounted an adjustable valve *x* of hollow cylindrical form for controlling communication between the high-pressure cylinder part and its delivery pipe *o*, the inner end of the valve being of closed conical form and adapted to co-operate with a complementary seating *y* in the extension, and the delivery pipe being connected to the extension at the side of the valve seating remote from the cylinder. The valve *x* is held on its seating by a spring *z* situated in the interior of the cylinder extension *d*¹, and the pressure exerted by the spring can be adjusted by a screw *2* passing

through a cover 3 on the outer open end of the extension. The screw 2 is adapted to act on the spring 2 through a thrust piece 4, in the cylinder extension d^1 , and is provided at its outer end with a hand operable hollow actuating head 5 suitably graduated to indicate the pressures required. Before the valve x can be lifted off its seating a predetermined pressure must be attained in the high-pressure part d of the cylinder. When this pressure is reached the valve x opens and establishes communication between the high-pressure part d of the cylinder and the delivery pipe o , the valve being thereafter held off its seating by the air pressure acting on the full area of the closed end of the valve. When the air pressure is released the valve x is returned by its spring z . In the cylinder extension cover 3 is provided an adjustable vent 6. To prevent air from leaking past the valve x to the vent 6 when this valve is open, the cover 3 is provided with a seating 7 against which the outer open end of the valve can abut when the latter is in its open position.

For regulating the pressure at which compressed air is admitted to the low-pressure cylinder part c , an adjustable reducing valve 8 and an adjustable choke valve 9 may be provided in the supply pipe i .

To the pipe j interconnecting the valve chest g and the low pressure part c of the cylinder I connect one end of a by-pass pipe 10, and I connect the other end of the latter pipe to the pipe t interconnecting the other valve chest r and the die casting machine v or other apparatus to be supplied with compressed air from the intensifier. In the by-pass pipe 10 is arranged a non-return valve 11, an adjustable choke valve 12, and (if desired) an adjustable reducing valve 13.

The apparatus above described is such that on admitting relatively low pressure air to the low pressure part c of the intensifier, air is at the same time supplied to the die casting machine v or other apparatus through the by-pass pipe 10, the pressure of this air being variable to suit different requirements by adjustment of the choke valve 12, and also of the regulating valve 13 (when used). Subsequently air at high pressure is supplied to the die casting machine v or other apparatus from the high pressure part d of

the intensifier when the pressure in the latter becomes sufficient to open a loaded valve x situated in the extension d^1 of that part.

By the use of a by-pass in combination with the intensifier and operating valves as above described I am able to effect the operation of a die casting machine and to adjust the working conditions to suit different alloys in a very satisfactory and convenient manner.

10 The invention is not limited to the example above described as subordinate constructional details may be varied. Moreover whilst the invention is especially intended for use with die casting machines it may be applied to other analogous uses where it can be advantageously employed.

15 Having thus described my invention what I claim as new and desire to secure by Letters Patent is:

20 Means for supplying compressed air to a die casting machine or other apparatus, comprising in combination a ram having a pair of parts of different diameters, a cylinder in which the ram is arranged and which is provided with high and low pressure parts of appropriately different diameters for accommodating the ram parts, the ram and cylinder being capable of relative sliding movement under the action of compressed air in the direction for compressing air in the high pressure cylinder part, a non-return valve 25 past which air can flow to the high pressure part of the cylinder, inlet and exhaust valves associated with the low pressure part of the cylinder, a delivery valve associated with the high pressure part of the cylinder, a passage through which compressed air from the high pressure part of the cylinder can flow under the control of the delivery valve, an air-release valve associated with the said passage, means whereby the inlet and exhaust valves are operatively interconnected with the delivery and air-release valves, 30 a by-pass situated between the inlet valve and a part of the said passage at the side of the delivery and air-release valves remote from the ram, a non-return valve arranged in the by-pass so that air from the inlet valve can flow through the by-pass to the said passage, and at least one 35 regulating valve in the by-pass.

40 45 GEORGE NORMAN CADBURY.
